UNITED STATES PATENT OFFICE

101,896

DESIGN FOR AN ELECTRIC FOOD CHOPPER OR SIMILAR ARTICLE

Hermann M. Alfred Strauss, Chicago, Ill., assignor to A. F. Dormeyer Mfg. Co., Chicago, Ill., a corporation of Illinois

Application September 11, 1936, Serial No. 64,810

Term of patent 14 years

To all whom it may concern:

Be it known that I, Hermann M. Alfred Strauss, a citizen of the German Republic, residing at Chicago, in the county of Cook and State of Illinois, have invented a new, original, and ornamental Design for an Electric Food Chopper or Similar Article, of which the following is a specification, reference being had to the accompanying drawing, forming part thereof.

Fig. 1 is a side elevational view of the electric food chopper showing my design.

Fig. 2 is a front elevational view.

Fig. 3 is a top plan view.

I claim:

The ornamental design for an electric food chopper or similar article as shown.

HERMANN M. ALFRED STRAUSS.
